UNITED STATES PATENT OFFICE.

DAVID H. WILSON, OF PATERSON, NEW JERSEY.

ELECTRIC WELDING SYSTEM.

1,307,030.

Specification of Letters Patent. Patented June 17, 1919.

Application filed December 31, 1914, Serial No. 879,955. Renewed February 24, 1916. Serial No. 80,125.

To all whom it may concern:

Be it known that I, DAVID H. WILSON, citizen of the United States, and resident of Paterson, in the county of Passaic and State 5 of New Jersey, have invented certain new and useful Improvements in Electric Welding Systems, of which the following is a specification.

My invention relates to a system useful in 10 electric welding with an arc.

One of its features is a resistance normally in the circuit before the arc terminals are brought into contact and which, when the terminals are brought into contact, operates to prevent a too great flow of current 15 across them.

My invention further consists of a circuit controller to automatically raise the voltage across the arc terminals to compensate for 20 the rising resistance due to the separation of said terminals while forming the arc.

In the drawings:—

The figure shows a diagram of my circuits and apparatus.

25 From a suitable source of welding current 1, a circuit is established by way of a conductor 2, through the regulating solenoid 3 and the solenoid 4 in multiple, conductor 5, through the carbon pile 6, to the hand tool 7, adapted to carry the metal welding pencil 8. This pencil is adapted to be brought into contact with the work 9 which forms the other terminal of the arc and which is connected by way of conductor 10 to the positive electrode of the source of current 1. 30 The carbon pile 6 is subject to the influence of the lever 11 pivoted at 12 and adapted at 13 to exert a heavy pressure upon the pile from 1500 lbs. down to 800 lbs. according 35 to the current in the solenoid, owing to the influence of the compression spring 14, normally inactive, and to the influence of the solenoid 3. The spring 14 is caused to exert an upward pressure upon the lever 11, when 40 the solenoid 4 is energized. This solenoid attracts the armature lever arm 15, so that its socket end 16 lifts the ball-shaped end 17 of the spring (against the tension spring 18) so that it exerts a powerful pressure upon 45 the spring 14, thereby exerting a pressure upon the pile.

The lever 11 is prevented from opening the pile beyond a certain limit by means of the abutment 19 which may be an adjusting screw mounted in a fixed support 20.

When the pencil is brought into contact with the work 9, current energizes the solenoid 4 which at once exerts a spring pressure upon the lever 11 to reduce the resistance of the pile. The solenoid 3, however, 60 has been energized at the same moment that solenoid 4 was energized so that the lever 11 is subject to a downward pull by the solenoid. The pressure of these two opposing forces is such that the lever 11 strikes a 65 balanced relation between the two. This happens the instant that current passes from the terminal 8 to the terminal 9. Thereafter as the terminal 8 is lifted from the terminal 9, the resistance at the arc is increased, the current flowing through the solenoid 3 is reduced, the pull of the solenoid upon the lever 11 is reduced, the spring 14 exerts a greater pressure upon the pile 6, and the resistance of the pile is thereby reduced. This operation continues as the arc is drawn until it is established. Thereafter, 70 any variation in the arc causes a corresponding variation of the current in the solenoid 3 which at once influences the lever 11 and 75 its pressure upon the pile 6. The resistance of the pile is varied inversely as the resistance of the arc. After the solenoid 4 has once acted, any weakening of the current flowing through its coils has no effect upon 80 the lever 15 and no effect upon the spring 14.

The spring 14 has an established length such that in the active position shown in the drawing it exerts a pressure upon the lever 11 sufficient to put a given maximum 85 pressure of say 1500 lbs. on the pile. When the armature lever arm 15 is released by the solenoid 4, it is drawn to the left by the tension spring 18 increasing the distance from the lever 11 to the socket 16, so that the ball-shaped bottom of the spring support 22 is lifted off from the socket, owing to the tension rod 21 taking the compression of the spring.

The abutment 19 then exerts a pressure 100 upon the lever 11 to produce a given minimum pressure upon the pile of about 800 lbs. for example. Between these maximum and minimum limits, the pile acts to the best advantage.

105 Many variations of my system may be made.

What I claim is:—

1. In a welding system, in combination, 110 a source of welding current, two arc termi-

- nals in manually operable space relation, means in circuit therewith operating with a graduated inverse reaction to limit initial arc flow, and a coacting series controller 5 gradually acting on said means to automatically vary the voltage across said terminals in compensating opposition to variations of arc resistance.
2. In a welding system, in combination, 10 a source of welding current, two arc terminals in manually operable space relation, means in circuit therewith operating with a graduated inverse reaction to limit initial arc flow, and a coacting series controller 15 gradually acting on said means to automatically vary the voltage across said terminals in compensating opposition to variations of arc resistance, and means responsive to cessation of welding current to automatically 20 restore said apparatus to initial condition after rupture of the arc, said means comprising a spring actuated toggle and an electromagnet opposed to the spring effort thereon.
3. In a welding system, in combination, 25 a source of welding current, two arc terminals in manually operable space relation, means in circuit therewith operating with a graduated inverse reaction to limit initial arc flow, and a coacting series controller 30 gradually acting on said means to automatically vary the voltage across said terminals in compensating opposition to variations of arc resistance, and means responsive to cessation 35 of welding current to automatically restore said apparatus to initial condition after rupture of the arc, said means comprising a spring actuated toggle and an electromagnet opposed to the spring effort 40 thereon, and a lever interposed between the toggle and the current graduating means and comprising a floating solenoid core, and a solenoid coacting therewith in parallel with the aforesaid electromagnet.
4. A welding system comprising a source 45 of welding current and a welding circuit including current-regulating means responsive to flow of welding current to introduce a given constant current-limiting effect and a variable current-limiting effect superposed thereon and tending compensatively to gradually increase the flow of welding current as the increase of welding resistance tends to decrease said current flow.
5. A welding system comprising a source 50 of welding current and a welding circuit connected therewith and including current-regulating resistance and electro-responsive means in control thereof and adapted and arranged to introduce a fixed resistance 60 component in response to initial flow of welding current and to introduce a compensatively varying resistance component in response to variations in strength of the welding current.
6. A welding system comprising a source 65 of welding current and a welding circuit connected therewith and including resistance-varying means and two electro-responsive devices in control thereof, one responsive to initial flow of welding current to produce a fixed effect on the resistance-varying means and the other responsive to variations in the intensity of said current to produce a graduated compensative effect on 75 said resistance-varying means.

Signed at New York in the county of New York and State of New York this 17 day of Dec. A. D. 1914.

DAVID H. WILSON.
